UNITED STATES PATENT OFFICE.

JAMES G. NOLEN, OF CHICAGO, ILLINOIS, ASSIGNOR TO JOHN E. SHEPHERD, OF CHICAGO, ILLINOIS.

SIGNALING SYSTEM.

No. 927,377.

Specification of Letters Patent.

Patented July 6, 1909.

Application filed October 4, 1905. Serial No. 281,229.

To all whom it may concern:

Be it known that I, JAMES G. NOLEN, citizen of the United States, residing at Chicago, in the county of Cook and State of Illinois, have invented a certain new and useful Improvement in Signaling Systems, of which the following is a full, clear, concise, and exact description, reference being had to the accompanying drawings, forming a part of this specification.

My invention relates to a combined fire alarm and watchman's signaling system, and has for its object a more simplified arrangement of the circuits therefor and of apparatus employed in connection therewith. In a system of this kind provision must be made for at all times keeping the line and apparatus in condition to send and receive fire alarm signals without interference from the watchman's signals, also to provide means for preventing manipulation of the apparatus by the watchman from giving fire alarm signals, and also to have the system well in test at all times so that defects therein can be detected at the central exchange, and so that provision can be made at the central exchange for so changing the circuits that the proper signals can be sent from every station on the line.

My invention, therefore, contemplates improved means for carrying out these necessary features.

My invention will be better understood by reference to the accompanying drawings, in which—

Figure 1 is a diagrammatic representation of a circuit and the station and central apparatus associated therewith. Fig. 2 is a front elevation of a station box, parts being broken away to reveal interior arrangements, and Fig. 3 is a sectional view taken on line 3—3 of Fig. 2.

The box 1 is provided with the cover 2 having an opening 3 which is covered by the glass plate 4 in a manner well known in the art. At the interior of the box is the partition wall 5 extending downwardly from the top of the box and the partition wall 6 extending upwardly from the base of the box, the partitions at their ends being separated to leave the intervening slot or passageway 7. An actuating arm 8 is pivoted to the post 9 extending from the rear wall of the box and is provided near its front end with the finger rest 10. Actuation of the lever is resisted by

spring mechanism, as for instance by the flat spring 11 secured at its rear end in the post 9 and bearing between the pins 12 secured in the lever. A toothed wheel 13 is secured to the lever concentric with its pivot point and is engaged by the escapement mechanism 14. At the front end of the arm is secured the segment 15 which is concentric with the lever pivot and which at its outer periphery has the code teeth 16 properly spaced for any required signal number, and suitably secured to a wall of the box is the switching circuit changing mechanism 17 whose actuating spring 18 is interposed to be moved by the teeth 16 upon actuation of the lever. This switching mechanism has also a contact spring 19 normally in engagement with the spring 18, and the springs 20 and 21 insulated from the other springs and normally in engagement. Extending through the partition wall 6 near the top is the detent rod 22 provided with the actuating head 23, this detent rod when pushed inwardly serving normally to hold the lever arm 8 in the position shown in Fig. 2.

A key hole 24 is provided through the cover of the box in such position that upon insertion and turning of the key the tail of the key will engage the extension 25 from the rear end of the actuating lever to cause the lever arm and the segment 15 to be rotated downwardly a sufficient distance to carry the code tooth series 16 beyond the end of the actuating spring 18. When the key has been turned sufficiently the extension 25 will be released and the spring 11 will return the lever arm to its normal position to rest against the detent rod 22. The teeth of the series 16, however, upon return of the lever successively engage the actuating spring to successively disconnect the spring from the normal contact spring 19 to correspondingly interrupt the circuit connected with said contacts. This series 16 corresponds to the watchman's signal, and the watchman by merely inserting and turning the key within the lock causes his number to be indicated on the central exchange instruments. If an alarm of fire, however, is to be given the glass plate 4 must be broken to gain access to the actuating head 23 which is pulled outwardly to withdraw the detent rod 22 from the path of the actuating lever which thereupon is moved upwardly by the spring 11 until it engages the stop 26. Upon

upward passage, however, of the segment 15 the teeth of the successive code sections 27 are moved across the point of the actuating spring 18 and the corresponding signal is 5 transmitted to the central exchange any number of times desired, in this case three. The person sending in an alarm may repeat the series any number of times by merely pressing the lever downwardly and releasing 10 it. The detent rod 22 is provided with a recess 28 for accommodating the latch 29 actuated by spring 30. Upon pulling out the actuating head 23 the end of the latch is depressed to engage below the edge of the 15 partition wall 6 and thus the detent is prevented from being returned to its normal position by the alarm sending. As is usual in systems of this kind, a special person is detailed to replace the apparatus after usage 20 thereof and the detent mechanism can easily be returned to lock the arm by inserting a suitable tool into the opening 31 to remove the latch 29 from the locking edge of the partition wall, and upon placing a new glass 25 plate within the opening the station box is again in shape to be operated by the watchman or for the purpose of sending fire alarm signals. The partition walls 5 and 6 serve to protect the operative parts and to prevent 30 interference therewith.

In Fig. 1 a number of station boxes are shown connected in a line which terminates at the central exchange in signal receiving apparatus. The line limb *a* at the central 35 exchange includes the winding 32 of the relay 33 and the source 34 of direct current being then connected to ground. The line limb *b* includes the winding 35 of the relay 36 and is also normally connected to ground 40 through a switch arm 37. An alternate contact 38 for this switch arm connects with the line limb *a* between the relay 33 and the source 34. The line limbs *a* and *b* serially include the spring mechanisms at the various 45 stations and the line is thus normally closed and the relays energized. The armature 39 of the relay 36 normally engages its front contact 40 and has an alternate contact 41. The armature 42 of the relay 33 normally engages its front contact 43 and has the back contact 44. A code signal receiving apparatus 45 is adapted for inclusion in circuit with the battery 46 and by means of the switches 47 and 48 this code mechanism is 55 adapted to be actuated when the relays are energized or when they become inert, the particular arrangement shown causing actuation of the mechanism when the relays become inert. As before stated, the springs 18, 19, 20 and 21 at each station are included 60 serially in circuit and the shape and adjustment of the springs 18 and 19 is such that there will be prolonged sliding contact between these springs before they are finally 65 disengaged upon engagement of the code

teeth on the segment with the actuating spring 18. The springs 20 and 21, however, are separated quickly upon actuation of the spring 18 by the code segment. The purpose of the prolonged engagement of the 70 springs 18 and 19 and the quick disengagement of the springs 20 and 21 is to avoid interference with the proper transmission of signals upon existence of defects in the system and will be explained more fully 75 later. The actuating arms at the various substations are connected together and with a common ground connection G.

Under normal conditions the operation is as follows: Current flows from the source 34 80 through the relay 33, line limb *a* and serially through the switch mechanisms at the stations to line limb *b* and through the relay 36, switch arm 37 to ground at the substation and back to the source 34, both relays being 85 energized and the signal producing circuit opened. Should the line be broken at any substation, as by the watchman inserting and turning the key, the actuating arm will be rotated as before described, and upon release will successively disengage the contact springs 18 and 19 to successively open the circuit whereby both relays are correspondingly deenergized and the circuit of the signal indicating apparatus correspondingly actuated. In the same manner the various code series will be transmitted over the line to be indicated upon the signal receiving apparatus upon manipulation of an actuating lever to sound a fire alarm. 90 Should the relays become inert without producing a signal the central attendant knows that the line is defective, this symptom being usually due to an open line. He therefore moves the switch arm 37 into engagement 100 with the contact 38 to connect both line limbs with the same terminal of the source and moves the switch arms 47 and 48 over to their respective alternate contacts so that the front contacts 40 and 43 are brought 110 into use. Thus the local circuit including the signal receiving apparatus 45 and the battery 46 is closed upon energization of either relay and as will be hereinafter described the signal may then be sent from any 115 station. For instance if the break occurred anywhere along the line limb *a* the relays will become inert, as there could be no ground connection to complete circuit to the source 34. When the attendant at the central station receives this signal he moves the switch arms 47, 48 and 37 over to their alternate contacts as above described. Suppose then, that an alarm is to be sent in 120 from station 12. As the lever thereat is actuated the actuating spring 18 will be connected to earth every time it is engaged by one of the code teeth, and as the contact between the springs 19 and 18 is prolonged 125 there will be a ground connection from the 130

line limb *b*. With each engagement of the switch spring 18 with a code tooth and before connection between springs 18 and 19 is broken, a complete circuit will be closed from the source 34 through the switch 37, through the relay 36, serially through the intervening switch mechanisms and through the springs 19 and 18 to the engaging tooth and through the actuating arm to the common ground G. The prolonged engagement of the springs 18 and 19 allows the simultaneous engagement of spring 18 with the code teeth and the spring 19 for a sufficient length of time for the relay 36 to be actuated, the relay becoming thus repeatedly energized in accordance with the particular code series and deenergized as the contacts 18 and 19 are disengaged. The local circuit including the signal receiving apparatus at the central station is therefore closed according to the code signal by the attraction of the armature of the relay 36 and the proper signal is therefore received at the central station. When a code tooth engages the spring 18 in the upward motion of the code tooth segment the springs 20 and 21 are immediately disengaged and any disturbance which might be on the line limb *a* on account of its defective condition will therefore be prevented from in any way affecting the further operations of the springs 18 and 19 which will then operate as above described. In the same manner upon actuation of apparatus at stations No. 21 and No. 22 relay 36 would control the signal receiving apparatus. If the break occurred in line limb *b* relay 36 would remain inert and relay 33 would control the signal indicating apparatus. A ground on either line limb will immediately manifest itself in the deenergization of relay 36, as the ground would short-circuit this relay. The central operator then would close the switch 37 with the contact 38 and the various stations would again be in proper circuit to send signals to the central exchange. If the ground appeared on line limb *a* the relay 33 would, of course, remain energized and the relay 36 would also become energized upon connection of the switch 37 with the contact 38. Actuation then of apparatus at any station will cause successive openings of the line upon disengagement of the contacts 20 and 21, and relay 36 becomes successively deenergized and the signal indicating apparatus will give the corresponding code signal. In the same way if the ground appeared on line limb *b* relay 36 would remain energized (the switch 37 being in connection with the contact 38) and relay 33 deenergized in correspondence with the code signals generated at the actuated station.

If the defect lies in a short circuit about the switching apparatus at one of the stations, as for instance at station 22 shown by

the dotted line, there will be no breaking of the line upon actuation of the station apparatus, as would be the case under normal conditions. When the short circuited substation apparatus is actuated, however, the line limb *b* will be connected directly with ground through the springs 19 and 18, the engaging code tooth and the common ground conductor. Thus the relay 33 will remain energized, being included in the following circuit: from ground through current source 34, relay 33, line limb *a*, through the various preceding switching apparatus, through the short circuiting path shown in dotted lines, through springs 19 and 18 and the engaging tooth to ground. The relay 36, however, is short circuited whenever this circuit is closed and will therefore be deenergized by each engagement of the spring 18 by a code tooth. Since no signal is received at the central station when such a short circuit is performed, the switch arms will remain in their normal position and the local circuit will be closed in accordance with the code signal when the short circuited apparatus is actuated precisely as when the line is in its normal condition. The prolonged engagement of the springs 19 and 18 affords a sufficient time constant for the proper operation of the relay 36.

The quick breaking contacts 20 and 21 are particularly effective in preventing interference from grounds with the effective operation of the particular controlling relay at the central exchange.

Thus by virtue of my improved arrangement of apparatus and circuits the system is operable under any of the defects which are usually prevalent in such systems. The apparatus at the stations is very simple of construction and employs a minimum number of parts and there is little liability, therefore, of its getting out of order very readily. I do not wish to be limited, however, to the exact construction of the apparatus and arrangement thereof and circuits as shown, as changes may readily be made without departing from the spirit of my invention.

What I claim as new and desire to secure by Letters Patent is:

1. In a fire alarm and signaling system, the combination with a line leading from a central exchange through a series of stations, of signal receiving apparatus at the central exchange, code teeth at each station, an actuating spring adapted for engagement with the code teeth, such engagement causing a break in the line at each side of said actuating spring.

2. In a fire alarm and signaling system, the combination with a line leading from a central exchange through a series of stations, of signal receiving apparatus at the central exchange, code teeth at each station, an actuating spring adapted for en-

gagement with the code teeth, and means adapted upon such engagement for entirely disconnecting said actuating spring from the line.

5 3. In a signaling system, the combination with a line leading from a central office through a series of stations, of code teeth at each station, switch mechanism having an actuating spring for engagement with said

10 code teeth, contacts adapted upon engagement of said actuating spring with the code teeth to be actuated to quickly open the line at one side of the actuating spring, and a second contact for the actuating spring

15 adapted upon engagement of said spring with the code teeth to have prolonged contact therewith and to be finally disconnected therefrom to open the line at the other side of the actuating spring.

20 4. In a signaling system, the combination with a line leading from a central exchange through a series of substations, of signal receiving apparatus at the central exchange, a pivoted actuating lever at each substation,

25 a segment concentric with said lever pivot having code teeth thereon, switch spring mechanism adapted to be actuated by said code teeth, said switch spring mechanism consisting of two pairs of contact springs, 30 one of said springs being adapted for engagement with the code teeth, such engagement causing a break in the line at each side of the actuating spring.

5. In a signaling system, the combination 35 with a line leading from a central exchange through a series of circuit controlling substations, of signal receiving apparatus at the central exchange, code teeth at each substation, an actuating switch spring adapted

40 for engagement with the code teeth, an auxiliary actuating spring operating with but insulated from said main actuating spring, and contact springs for each of said actuating springs, means adapted when said actuating 45 switch spring engages the code teeth for entirely disconnecting said switch spring from the line.

6. In a signaling system, the combination with a line leading from a central exchange

through a series of circuit controlling substations, of signal receiving apparatus at the central exchange, code teeth at each station, two actuating springs at each substation mechanically connected together and adapted to be actuated by said code teeth, 55 and a contact spring for each of said actuating springs, all of said springs being serially connected in the line circuit, one of said actuating springs being adapted to be separated from its contact spring immediately 60 upon the engagement of a code tooth thereby opening the line circuit, the other of said actuating springs having prolonged engagement with its contact spring whereby one side of the line may be connected with 65 ground connected with said code teeth.

7. In a signaling system, the combination with a line leading from a central exchange through a series of circuit controlling substations, of signal receiving apparatus at the central exchange, said signal receiving apparatus being controlled by relays connected between the line and a third conductor, code teeth at each station, said code teeth being connected with the third conductor, two actuating springs operating together adapted to be actuated by said code teeth, and a contact spring for each actuating spring, all of said springs being serially connected in the line circuit, one of said actuating springs being adapted to be separated from its contact 75 spring immediately upon the engagement of the other of said actuating springs with a code tooth, the actuating spring connecting with the code tooth being adapted to have 80 prolonged engagement with its contact spring whereby that side of the line connected with its contact spring may be connected with the third conductor, said contact spring engaged by said code tooth being 85 adapted to finally disconnect from its contact spring to break the circuit.

In witness whereof, I hereunto subscribe my name this 16th day of Sept. A. D. 1905.

JAMES G. NOLEN.
